UNITED STATES PATENT OFFICE.

LOUIS P. BRUNELLE, OF WINNIPEG, MANITOBA, CANADA.

VEST.

Application filed March 12, 1923. Serial No. 624,641.

To all whom it may concern:

Be it known that I, LOUIS P. BRUNELLE, of the city of Winnipeg, in the Province of Manitoba, Canada, and a subject of the King of Great Britain, have invented certain new and useful Improvements in Vests, of which the following is the specification.

The invention relates to improvements in vests and an object of the invention is to provide a collarless vest, cut in such a manner at the neck that the vest cannot work beneath the outer band of a double band or turn up turn down collar, as it is generally called.

With the above more important object in view the invention consists essentially in the vest construction hereinafter more particularly described and later pointed out in the appended claim, reference being had to the accompanying drawing in which:

Fig. 1 is a perspective view of the upper part a vest constructed in accordance with my invention.

Fig. 2 is a face view of the front part of the vest.

In the drawing like characters of reference indicate corresponding parts in the several figures.

I have found that the present open front collarless vest has at all times a tendency to work beneath the collar especially where a double band or turn up turn down collar, as it is usually called, is worn. The reason for this apparently is that in the customary vest the front opening of the vest gradually swings inwardly from a location at or near the shoulder seam of the vest, with the result that the vest in hanging from the shoulder seam naturally works in underneath the collar to the discomfort of the wearer.

According to my invention the vest 1 has the front opening 2 formed so that that part 3 at the neck lies parallel with the collar 4 for a short distance beyond the shoulder seam 5. Accordingly, when the vest is in use there is no possibility of the same working under the collar as it is cut to sit up on the collar to a position in advance of the shoulder seam, after which it swings down into the customary front opening 2.

In order to better understand the invention I have shown the front pattern of the

vest in Figure 2. In this figure the shoulder seam is indicated at 5, the arm hole opening at 6, and the neck stand at 7.

According to present practice the front opening of the vest is cut in a continuous gradual curve, as indicated by the dotted line A in Fig. 2. According to my invention, however, the inner side 8 of the neck stand is cut to follow parallel with the collar to a position indicated at 9 somewhat in advance of the shoulder seam and the front opening 2 of the vest continues in the manner shown, from the point 9.

By cutting the vest fronts to such a pattern it will be found that the vest will sit on the collar in the manner shown in Fig. 1 and obviously there is no possibility of the vest working underneath the collar. This form of vest also avoids creases forming in the vest at the shoulder front. Obviously, the point 9 could be advanced or withdrawn as wished, depending on the amount of opening fashion required in the front of the vest.

I have found also that an old or used vest can be modified according to my invention by cutting it along the dotted line B, Fig. 2, it being here borne in mind that the dotted line A, indicates the original cut of such vest. By making the cut B as shown in the vest I bring it practically into the same form as shown in full outline in the pattern, Figure 2, and I will provide a point 9' which actually will correspond to that 9 hereinbefore described. After being so cut and finished the neck part of the vest, or that above the point 9' will have a natural tendency to sit up on the collar and in so doing I obtain the same results as described in connection with the original pattern.

In this connection I might remark that I actually took a vest, the cloth of which had been worn to a cut by the collar, and by cutting it as indicated by the dotted line B and making the point 9' virtually the worn out or cut part of the vest I repaired it so that when worn it sat well up on the collar band.

Whilst I have stated that the vest was cut along the dotted line B I wish it to be understood that the dotted line B indicates the edge of the vest opening and it is immaterial whether it be cut at this point

and finished or turned in to follow the dotted line B.

What I claim as my invention is:—

A collarless vest having the neck and vest 5 front openings cut to meet at obtuse angles in a location in advance of the vest shoulder seams.

Signed at Winnipeg, this 19th day of February 1923.

LOUIS P. BRUNELLE.

In the presence of:

GERALD S. ROXBURGH,
M. B. KELLEHER.
